UNITED STATES PATENT OFFICE.

JAMES A. WILSON, OF ARKANSAS CITY, KANSAS.

IRRIGATING-TILE.

1,070,760.

Specification of Letters Patent. Patented Aug. 19, 1913.

Application filed August 1, 1912. Serial No. 712,715.

To all whom it may concern:

Be it known that I, JAMES A. WILSON, a citizen of the United States, residing at Arkansas City, in the county of Cowley and State of Kansas, have invented certain new and useful Improvements in Irrigating-Tiles; and I do declare the following to be a full, clear, and exact description of the invention, such as will enable others skilled in the art to which it appertains to make and use the same.

This invention relates to improvements in irrigating tiles.

One object of the invention is to provide a tile of this character from which the water is drawn by a seepage or capillary attraction of the soil so that only the proper quantity of water is taken from the tile of the irrigating system as is needed to maintain the desired degree of moisture in the soil.

Another object is to provide an irrigating tile having means whereby the same forms a reservoir for holding a greater or less quantity of water as desired.

With these and other objects in view, the invention consists of certain novel features of construction, combination and arrangement of parts as will be more fully described and claimed.

In the accompanying drawings; Figure 1 is a central vertical sectional view of a portion of an irrigating system employing my improved tile and illustrating the latter arranged to form a deep reservoir; Fig. 2 is a similar view showing the tiles arranged to form a shallow reservoir; Fig. 3 is an enlarged central vertical longitudinal section of one of the improved tiles; Fig. 4 is a cross sectional view of the same, taken on the line 4—4 of Fig. 3.

Referring more particularly to the drawings, 1 denotes my improved tile which is preferably round in cross section and tapers slightly from one end toward the other as shown. The tiles are preferably formed of cement and sand with only about eight or ten per cent. cement which is mixed very dry barely enough moisture being employed to pack the material. The tile when thus constructed dries very hard but remains sufficiently porous to permit the water to seep or be drawn therethrough by the capillary attraction of the soil in which the tile is laid.

Across the inside of the smaller end of the tiles are formed transversely disposed dams 55 or obstructions 2 which project beyond the inner side of the tile for a suitable distance as shown. When the tiles are laid in the position shown in Fig. 1 wherein the dams 2 are disposed at the lower side of the tile, 60 it will be seen that these dams will hold back a much larger quantity of water in each tile than would be held by the inclined surface alone. In thus holding back the water a larger surface of the tile is covered by the 65 water thus permitting a greater quantity of the water to seep through the tile. When less water is required the tiles are laid in the position shown in Fig. 2 of the drawings wherein the dam is disposed at the top or in 70 the upper portion of the tile so that only so much water remains as may be held by the inclined or tapered formation of the tile. As this lesser quantity of water covers less space on the inner side of the tile the seep- 75 age action or discharge of the water is correspondingly decreased.

By means of the tile constructed and arranged as herein shown and described, it will be seen that an even distribution of water will be had when the tiles are laid in the manner described and that the water will percolate or pass through the porous sides of the tile only as it is needed and drawn therethrough by the capillary attraction of the 80 surrounding soil, or, in other words, when this soil has obtained sufficient moisture the capillary attraction or absorption of the water through the sides of the tile will cease until the soil has again become dry and in a 85 condition to absorb more moisture at which time the capillary attraction of the dry soil will again cause the water to seep through the tile as will be readily understood. When the telescoping tubes 1 are united in 90 the manner previously described and with their ends connected as shown the supply of water passing through the pipe thus formed can be accurately adjusted by turning the sections of the same independently of one 95 another to the desired position, the particular formation of the dams 2 at the reduced ends of the sections forming a valve between consecutive sections. Thus it will be seen 100 that the connected inclined telescopic sections forming the tube provide intervening cham- 105

bers for receiving the water, a greater portion of the latter being located in the enlarged expanded ends of the sections, and further that when a minimum amount of water is directed through the tube thus formed the projections or dams 2 form an obstruction against which the water is directed.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as defined and claimed.

Having thus particularly described my invention, what I claim is:

A device of the character described comprising a plurality of tapering detachable porous irrigating tiles which are telescopically connected and adapted to be rotatably adjusted in respect to one another, and a dam forming an integral part of each of said sections and located adjacent to the reduced end thereof.

In testimony whereof I have hereunto set my hand in presence of two subscribing witnesses.

JAMES A. WILSON.
